CLOTHESLINE PEG

Geoffrey Maxwell Gibbs, Sawbridgeworth,
England

Application April 23, 1951, Serial No. 14,929

Term of patent 7 years

(Cl. D49—1)

To all whom it may concern:

Be it known that I, Geoffrey Maxwell Gibbs, a subject of Great Britain, residing at The Bungalow, Maylins Acre, Sawbridgeworth, Hertfordshire, England, have invented a new, original and ornamental Design for a Clothesline Peg, of which the following is a specification, reference being had to the accompanying drawing, forming part thereof.

I claim:

The ornamental design for a clothesline peg, as shown.

GEOFFREY MAXWELL GIBBS.
